UNITED STATES PATENT OFFICE.

EDGAR D. TILLYER, OF SOUTHBRIDGE, MASSACHUSETTS, ASSIGNOR TO AMERICAN OPTICAL COMPANY, OF SOUTHBRIDGE, MASSACHUSETTS, A VOLUNTARY ASSOCIATION OF MASSACHUSETTS.

APPARATUS AND PROCESS FOR PRODUCING OPHTHALMIC LENSES.

Application filed March 30, 1925. Serial No. 19,456.

This invention relates to an improved apparatus and process for producing ophthalmic lenses, and has particular reference to the provision of apparatus and a process for producing multifocal lenses from a single piece of glass.

Prior to this invention there have been a number of methods used to produce multifocal lenses from a single piece of glass, practically all of which methods embodied separate grinding and polishing operations to produce the different focal fields. Such grinding and polishing operations have been very difficult to perform and have required special and expensive machinery and skilled labor to operate the same, all of which has resulted in the lenses being high in cost. One of the desirable characteristics of such lenses lies in the merging of the adjacent focal fields so that the line of division between said fields would be substantially invisible. To produce the fields with such merging has been a difficult manufacturing task, and a large percentage of blanks have had to be scrapped because one surface has not merged with the other.

By my improved means I propose to produce multifocal lenses with merged surfaces without having to resort to the difficult grinding and polishing operations as performed in the prior art.

An important object of the present invention is to provide apparatus and an improved process for producing multifocal lenses whereby an optical addition will be provided in a lens blank by molding.

Another object is to provide such apparatus and a process making use of pneumatic action in displacing a portion of a finished optical surface.

Another object is to provide such apparatus and process utilizing a suction to produce the desired addition.

Still another object is to provide such apparatus and process whereby an optical addition may be produced upon a continuous finished surface without injuring the same.

Another object is to provide such apparatus and process whereby the dioptric value of the optical addition may be controlled at will by the amount of suction or the duration of its action.

Other objects and advantages will be

apparent from the following description taken in connection with the accompanying drawings, wherein the apparatus and steps of the process are diagrammatically illustrated.

In the drawings,

Figure 1 is a transverse sectional view through a lens blank and a supporting block therefor as used in the improved process;

Figure 2 is a vertical sectional view illustrating the lens blank being operated upon within a heating chamber;

Figure 3 is a view similar to Figure 2, showing a different type of blank in the course of production;

Figure 4 is a front elevation of a completed lens blank;

Figure 5 is a vertical transverse sectional view through the same.

Figure 6 is a vertical sectional view illustrating a different method of operating upon a lens blank to obtain the same result as that of Figure 2.

Similar reference characters designate corresponding parts throughout the several views.

In carrying out the invention I first provide a lens blank 10 with a finished optical surface 11 upon one side thereof. The lens blank may be either plano in form, convex, or concave, as is desired, and the finished surface 11 must correspondingly be prepared upon the surface to which the optical addition is to be made. I then place the blank 10 upon a refractory supporting block 12 with the finished optical surface 11 exposed, as clearly shown in Figure 1, whereupon I place the block and the blank in a suitable heating chamber or oven 13, which is diagrammatically shown in Figure 2. This oven 13 preferably comprises side walls 14 and a top member 15 any of which may be apertured if desired to give ventilation. Electrical or other heating elements 16 are disposed within the chamber 13 and adapted to supply sufficient heat to render the lens blank 10 soft and substantially plastic.

When the blank has thus been softened by the action of heat, a suction cup 17 is brought into engagement with the finished optical surface 11 of the blank. It is to be noted that the suction cup 17 is preferably circular in transverse section, and provided with a sharp annular edge 18, which is

adapted to contact with the surface 11 without injury thereto. After the suction cup has thus been positioned, the pressure within the same is reduced to a sufficient degree 5 to draw up the covered portion of the surface 11, as clearly shown at 19, thus producing a curved surface of a different radius from the major surface 11. In this operation the rear or bottom surface of the blank 10 is also drawn up, as shown at 20, forming a rather irregular depression, which must afterwards be ground away.

In order to facilitate ready manipulation and to make it adaptable to different curvatures of lens blanks, the suction cup 17 is mounted upon a sleeve 21 which is slidable within a ball socket 22 pivotally mounted in the cover 15 of the heating chamber. Of course, there are a great many different 20 materials which may be employed in the suction cup 17, but one of the principal requirements is that it shall be able to withstand the action of heat, and furthermore that the glass will not have a tendency to adhere 25 to its annular contacting surface. One very desirable material for this purpose is graphite, but of course block carbon or certain kinds of metal may also be used advantageously. The outer extremity of the sleeve 21 is connected by means of a flexible conduit 30 to a suction pump or other suitable device.

In Figure 3, I have illustrated a lens blank 10^a in which the concave surface has been previously finished, and to which the 35 optical addition is to be applied as at 19^a. From this it will be readily appreciated that the operation may be performed upon either side of a lens blank regardless of its shape.

After the blank 10 on the supporting block 12 is placed in the heating chamber 13, the temperature is gradually increased until it reaches approximately 1000 to 1400 degrees Fahrenheit, under which temperature 45 the glass becomes sufficiently softened for this operation, whereupon the cup 17 is applied and a portion of the lens thereby actuated by suction. It is to be noted that the dioptric value of the optical addition 19 50 may be controlled at will by the amount of the suction or the duration of its action upon the glass, so that in this way multifocal lenses of any desired addition may be conveniently produced.

55 After the previously finished surface is thus formed, the blank is removed from the heating chamber and the bottom side 24 is eventually ground off to remove the depression 20 and to produce a finished optical surface 25 on the reverse side of the blank; thus a complete lens is formed which may be cut to any size, for example as illustrated by dot and dash line 26 in Figure 4, and thereafter applied to a spectacle or 60 eyeglass mounting.

In carrying out the invention I do not limit myself to the use of a suction for displacing a portion of the finished surface of the lens blank, since any other method of pneumatic pressure variation upon the 70 different portions of the surface may be employed.

For example, as illustrated in Figure 6, a lens blank 27 supported by a refractory block 28 is positioned within a heating chamber 29, wherein it may be softened by means of the usual heating elements. In this form of the invention a tube 30 is slidably mounted within a ball and socket joint 31, said tube having its lower or inner end tapered to a knife edge as at 32 for contact with the finished surface of the lens blank. The upper or outer end of the tube 30 is open to the atmosphere as at 33, instead of being connected to a suction pump as in 80 the previous embodiment. The heating chamber 29 is completely enclosed by the walls of the oven 34 and at the proper time is supplied with fluid or pneumatic pressure through a pipe 35 extending from any suitable source of supply.

With this form of the invention after the blank 27 has been suitably softened and the tube 30 applied to its surface, as clearly shown, compressed air or other suitable medium is supplied through the pipe 35 to the chamber 29 so as to apply a pressure to that portion of the finished surface of the blank which surrounds the extremity 32 of the tube 30. Since this pneumatic pressure 100 is greater than that of the atmosphere within the tube 30, that portion of the blank covered by the end of the tube will be displaced as at 36 because refractory blocks such as fire brick and carborundum which 105 are commonly used for supporting plastic lenses are porous and the increased pressure in the chamber 29 will exert a pressure up through the porous block 28 and cause the plastic glass to be displaced upwardly into 110 the tube 33, the extent of said displacement being controllable at the will of the operator by regulating the pressure in the chamber 29.

From the foregoing it will be evident that 115 I have provided a process which is especially adaptable for production of multifocal ophthalmic lenses, and which will be simple to apply in practice and economical to carry out. By virtue of the fact that no 120 material touches the finished surface 11 while the blank is in the softened condition, there will be no necessity for afterwards either grinding or polishing the multifocal surface. Obviously changes may be resorted to in the details and arrangement of the 125 steps of the process, and the right is herein reserved to make such changes as fall within the scope of the appended claims without departing from the spirit of the invention. 130

Having thus described my invention, I claim:

1. The process of producing multifocal lenses comprising finishing a piece of glass to a polished lens surface, heating the glass to plasticity and drawing up a portion of the polished surface to a different curvature by suction applied to the polished surface without the said displaced polished surface 10 coming in contact with anything to shape it.
2. The process of producing multifocal lenses comprising finishing a piece of glass to a polished lens surface, heating the glass to plasticity and pneumatically displacing a portion of the polished surface to a different curvature without the said displaced polished surface coming into contact with anything to shape it.
3. The process of making multifocal lenses comprising finishing a piece of glass to a polished lens surface, heating the glass to plasticity, and displacing a portion of the polished surface to a different curvature by varying the atmospheric air pressure 25 sure on the lens whereby a portion of the polished surface is displaced to a different curvature without said displaced surface coming in contact with anything to shape it.
4. In a device of the character described, 30 a block for supporting a heated lens, a tube having an annular edge contacting with the outer face of the lens, and suction means attached to the tube to draw up a portion of the lens into the tube.
5. In a device of the character described, 35 a block for supporting a heated lens, a tube having an annular edge contacting with the outer face of the lens, and a pneumatic coupling attached to the tube adapted to change the atmospheric pressure on the lens 40 in the portion thereof covered by the annular edge of the tube.
6. In a device of the character described, 45 a block for supporting a heated lens, a tube having an annular edge contacting with the outer face of the lens, a pneumatic coupling attached to the tube, and a universal bearing on the tube adapted to position the tube on the lens in desired position.
7. In a device of the character described, 50 a block for supporting a heated lens, an oven surrounding the block, means to heat the oven, a tube having an annular edge adapted to contact with the outer face of the lens, a pneumatic coupling attached to 55 the tube adapted to change the atmospheric pressure on that portion of the lens within the annular edge of the tube and means for mounting the tube whereby it may be moved to desired position on the lens.
8. The process of making a multifocal lens comprising polishing a piece of glass to a polished lens surface, heating the glass to plasticity, resting an annular compress on the polished surface, and changing the 60 air pressure on the glass to force a portion of the polished surface up into the compress without touching anything.
9. In a device of the character described, 65 a block for supporting a heated lens, a tube having an annular edge resting on the outer surface of the lens, and means for changing the atmospheric pressure on the lens to force a portion of the outer surface up into the tube without said displaced surface contact- 70 ing with anything.
